W. P. NEWELL.

BROOM.

APPLICATION FILED MAY 14, 1915.

1,153,104.

Patented Sept. 7, 1915.

UNITED STATES PATENT OFFICE.

WARREN PARKER NEWELL, OF HORTON, KANSAS.

BROOM.

1,153,104.

specification of Letters Patent. Patented Sept. 7, 1915.

Application filed May 14, 1915. Serial No. 23,018.

To all whom it may concern:

Be it known that I, WARREN P. NEWELL, a citizen of the United States, and a resident of Horton, in the county of Brown and State 5 of Kansas, have invented certain new and useful Improvements in Brooms, of which the following is a specification.

My invention relates to brooms, and the main object thereof is to provide means for 10 utilizing the hitherto wasted coarser ends of the broom corn without any sacrifice of the finer ends as now utilized.

A further object is to provide a broom which effects a considerable saving to the 15 consumer by not alone doubling the life thereof by the provision of two operative ends but also providing a rough broom for rough work and a fine broom for finer work, and correspondingly increasing the life of 20 the broom by the conservation of the finer ends.

A further object is to mount the broom in a suitable carrier or handle in such manner as to allow the use of either end of the broom 25 by the provision of a readily opened and closed lock for the broom in either of its two positions.

A still further object is to still further contribute to the economy of the broom expense of a consumer by the provision of the 30 brooms separately from the handle or carrier and readily operable means for removing a worn broom from the handle and attaching a new broom thereto, said handles 35 lasting indefinitely, and the brooms being carried in stock by dealers and sold at relatively low prices, according to size and grade.

My invention is fully described in the following specification, of which the accompanying drawings form a part, in which like characters are used to refer to like parts in each of the views, and in which:

Figure 1 is a perspective view of the broom and handle joined for use; Fig. 2 is 45 an enlarged face view thereof, partly broken away; Fig. 3 is a side or edge view of the device; and Fig. 4 is a section taken on the line 4—4 of Fig. 2, and indicating by broken lines the intermediate position of the broom 50 in being moved from one operative position to the other, and for storing the broom when not in use, when the same is resting upon a floor or the like.

In the drawings forming a part of this application I have shown a present preferred embodiment of my invention, comprising a

broom member 5 and a carrier 6 formed of a yoke 7 having a pole or handle 8 connected therewith, preferably detachably, and the ends of the arms of said yoke are flattened 60 and drilled as shown at 9, Figs. 2 and 3.

The broom proper consists of a suitably shaped bundle of hairs or splints of equal lengths, flat as shown, clamped together centrally of their lengths by means of a 65 strong band 10 which forms a component part of the broom when vended, and the coarser ends of the hairs or splints are all preferably at one end, 11, of the broom and the finer ends at the other end, 12, thereof. The ends of the band 10 are secured to the 70 respective arms of the yoke 7 by means of screws 13 engaged in the flattened ends 9 thereof, whereby the broom member may be revolved end for end when desired, to bring 75 either the coarse or the fine end into operative position.

In permanent connection with one arm of the yoke 7 is a hook member 14 and a pin 15 adjacent thereto, a rod 16 being in 80 pivotal connection with said arm between said hook and pin, as clearly shown in Figs. 2, 3, and 4, the rod 16 being of a length exceeding the width of the broom member. In similar connection with the other yoke arm 85 is a hook 17, pin 18, and rod 19, and it will be seen that the rod 16 may be sprung into and out of engagement with the hook 17, and the rod 19 may be sprung into and out of engagement with the hook 14; said rods 90 may be swung outwardly away from the broom to permit the revolution of the broom member on its pivots, and, when engaged with the respective hooks, said rods serve to lock the broom member against movement 95 with respect to the carrier or handle to permit the use of the device, as in sweeping, the finer ends of the splints being in outermost position for light uses, as in homes and the like, whereas the coarser ends will be 100 used outside the house, or when thorough cleaning of carpets and the like is desired.

The device as illustrated is intended for use as a floor broom composed of broom corn, but any desired material may be employed for desired uses, and I do not desire to limit myself to any specific material, size, or shape of the device.

The device, despite its advantages, is considerably more economical in manufacture 110 than the conventional brooms, inasmuch as the binding wire or cords are not used, nor

the finishing or ornamental ferrules and the like, and the machines now required wherein the coarse ends of the corn splints are bent inwardly, trimmed, and bound, are not needed for my devices.

My invention is very practical as well as economical, and with a reservation to myself of changes over the form shown and described as properly come within the scope of the following, what I claim as new, and desire to secure by Letters Patent, is:—

A broom, comprising a bundle of suitable material, a band around the same interme-

diate the ends thereof, a yoke having two arms in pivotal connection with opposite sides of said band, a hook secured to each arm, and a rod in pivotal connection with each arm and engaged by the hook of the other arm.

In testimony whereof I have signed my name to this specification in the presence of two subscribing witnesses.

WARREN PARKER NEWELL.
